(57) **CLAIM**

The ornamental design for a wing and drumette rack, as shown and described.

DESCRIPTION

FIG. 1 is a front, perspective view of a wing and drumette rack showing our new design, the wing and drumette rack, having a handle on either side, and feet to support the wing and drumette rack.

FIG. 2 is a top view of the wing and drumette rack of FIG. 1. FIG. 3 is a bottom view of the wing and drumette rack of FIG. 1.

FIG. 4 is a front view of the wing and drumette rack of FIG. 1; the front view being a mirror image thereof; and,

FIG. 5 is a right side view of the wing and drumette rack of FIG. 1; the left side view being a mirror image thereof.
